UNITED STATES PATENT OFFICE.

JOHN W. GILES, OF GREER, SOUTH CAROLINA, ASSIGNOR TO DRAPER CORPORATION,
OF HOPEDALE, MASSACHUSETTS, A CORPORATION OF MAINE.

AUTOMATICALLY THREADING SHUTTLE FOR LOOMS.

Application filed March 19, 1927. Serial No. 176,771.

This invention relates to loom shuttles which are automatically threaded during the loom operation when filling replenishment is effected, and is more particularly directed 5 to the thread tensioning means for imparting to the thread the desired tension as the shuttle is picked.

In the patent to Mr. Edward S. Stimpson, numbered 1,483,492, dated February 12, 1924, 10 an automatically threading shuttle for looms was shown, described and claimed, wherein the longitudinally extending thread passage or the threading block, usually mounted in the eye end portion of the shuttle, was supplied with a thread casting and guiding device, shown in one form in the patent as a scroll. Shuttles made in accordance with the Stimpson invention have been successful 15 in practical operation, and even though the shuttle may become partially or wholly unthreaded on the occurrence of overthrow as the shuttle comes to rest in the replenishing box, it is immediately rethreaded on the next pick of the shuttle. Owing to the fact 20 that the threading block or thread passage offers little or no retardation to the thread movement during weaving, it has been found desirable in weaving with certain kinds or characters of filling or thread to provide an 25 appropriate form of thread tensioning means which will impart to the thread the desired tension as it is laid in the shed.

An important feature of the present invention therefore consists in providing an 30 automatically threading shuttle for looms with a thread tensioning device positioned transversely of the longitudinally extending thread passage at a point adjacent the bobbin chamber, and to provide in the thread 35 passage between such thread tensioning device and the side delivery eye a thread guide which may act to maintain a proper control of the thread. In accordance with the general character of the invention, the thread 40 guide may be formed as a scroll located in the thread passage between the tensioning device and side delivery eye. On the first 45 pick of the shuttle following replenishment, the thread swirls or balloons around the end 50 of the filling carrier or bobbin in the bobbin chamber, and in the shuttle disclosed in the Stimpson patent, this swirling action of the thread enables the scroll to take control and 55 thereafter guide the thread during the movement of the shuttle for the thread delivery

through the side delivery eye. In devising a proper tensioning device for the thread and yet permit its swirling action to place the thread in the control of the scroll, the present invention provides a coiled spring, 60 between the convolutions of which the swirling action of the thread will tend to place the thread as the shuttle is picked, and consequently to pass into control of the thread guiding device in the longitudinally extending 65 thread passage.

In accordance with another feature of the present invention, the coiled spring tensioning device is mounted at the entrance of the thread passage with the top of the coils thereof slightly above a portion of the thread guiding device or scroll, with the result that when the thread has passed into control of the scroll, it will also be placed 70 between the convolutions of the spring coil and there remain until the occurrence of an overthrow.

In accordance with another feature of the invention, the coiled spring tensioning device is supported in a saddle secured to the loom shuttle adjacent the entrance to the longitudinally extending thread passage and thread guiding means is employed for engaging the swirling thread and directing it 75 to the coiled spring tensioning device.

The invention and novel features thereof will best be made clear from the following description and the accompanying drawings of one good form thereof.

In the drawings:
Fig. 1 is a plan view of the eye end of a shuttle of the automatically threading type, having the present invention associated therewith;

Fig. 2 is an enlarged cross-section on the line 2—2 of Fig. 1;

Fig. 3 is a perspective view of the shuttle of Fig. 1, containing the present invention;

Fig. 4 is a perspective detail, showing the saddle and the spring coil tensioning device being assembled.

The shuttle 1 is provided with the bobbin chamber 2 and forward of the bobbin chamber is the longitudinally extending thread passage 3 terminating in a bridge, laterally of which is the side delivery eye 4. In the illustrated form of the invention the shuttle is provided with a threading block 5, shown in the present instance as of substance

tially the same general character as the threading block in the Stimpson patent above mentioned, and mounted in the longitudinally extending thread passage is the 5 thread casting and guiding device 6, herein shown as in the form of a scroll, the free end portion of which extends frontwardly in the thread passage in substantially the same manner as more fully shown and described 10 in the Stimpson patent, the construction being such that should the thread overthrow as the shuttle is brought to rest in the replenishing box, the thread casting device will cause the thread to pass upwardly from 15 the thread passage and the shuttle become either partially or wholly unthreaded. On the next pick of the shuttle, however, the shuttle will become rethreaded in a manner similar to that described in more detail in 20 the Stimpson patent.

The thread tensioning device consists of a spring coil 7 which extends transversely of the thread passage adjacent the bobbin chamber, so that the scroll is between the 25 tensioning device and the side delivery eye and thus serves to guide the thread through the tensioning device.

As indicated in the drawings, the spring coil tensioning device 7 is supported by a 30 saddle 8, one of the side arms 9 of which is extended upwardly and at its upper end is provided with a portion 10 having an opening 11 for the reception of a screw or other securing device 12 for holding such side portions of the saddle in position adjacent the bobbin chamber.

The opposite side portion 13 of the saddle is similarly extended upwardly and at its upper end is bent or turned, as at 14, to provide a downwardly extending spring tension 40 adjusting member 15. The lower end portion of the spring tension adjusting member 15 is provided with an opening 16 and through said opening and holes 17 in the upwardly extending side members of the saddle is passed the bolt 18, one end of which may be suitably threaded, as at 19, to receive a nut or other securing means 20, and the bifurcated end portion 16 of the spring adjusting member 15 straddles the bolt and is guided thereby as it is bent more or less, as 50 will hereinafter be described, to properly space the coils of the spring tensioning device in accordance with the size of the thread in use.

The shuttle wood is recessed or cut away at 21, best shown in Fig. 2, to receive the upwardly extending side member 13 and the spring tensioning member 15 and house these 60 parts, especially at their upper portions, to prevent the thread from catching on any obstruction during its swirling action as it is withdrawn from the bobbin during weaving.

As will be noted in Fig. 2, the coiled spring

tensioning member 7 floats upon the transverse bolt 18 and is positioned in the longitudinally extending thread passage relative to the scroll 6, so that a portion of the said scroll is below the top surface of the coils, 70 constituting the thread tensioning member, the result being that when the thread has passed into the control of the thread guiding device or scroll 6, it will be drawn into the coils of the thread tensioning member into 75 a position as indicated at *a*, Fig. 2, and to maintain the parts in this associated relation the spring tensioning member is provided with an additional supporting device 80 to support the scroll relative to the supporting saddle. Such supporting device, as indicated in Figs. 2 and 4, may be constituted by a bent member 22, a simple form of which is shown as a wire having one leg 23 extending 85 downwardly at the outer side of the upwardly extending side member 13 and its upper portion formed as a loop, as at 24, from which point the wire is bent downwardly, at 25, to constitute a thread guide leading to the spring coil tensioning member. 90 The downwardly extending thread guiding portion 25 engages one of the side coils or convolutions of the spring tensioning member 7 and passes through an opening 26 in the adjusting member 15, and is then extended laterally through an opening in the upwardly extending side member 13 of the saddle, as indicated at 23, Fig. 2. The result is that the spring supporting member 22 acts 95 not only to hold the spring tensioning member 7 in its floating position at the entrance of the longitudinally extending thread passage, but also as a thread guide to engage 100 the swirling thread and direct it to a position upon or between the coils of the spring tensioning device.

In using thread of relatively large count or size, the convolutions of the spring tensioning member should be farther apart than when using thread of finer count or 110 smaller size, in order to gage the proper tension suitable to the thread in use. To effect proper adjustment of the convolutions of the spring tensioning member, the downwardly extending portion 15 of the saddle may be 115 bent in either direction, one to close the convolutions of the spring tensioning member, and the other to widen the space between the coils. To readily effect this character of adjustment, the saddle may be made 120 of appropriate material, such, for instance, as brass, composition, or other metal, so that by the insertion of an instrument from the bobbin chamber into the space between the side member 13 and the adjusting member 15, these two parts may be separated to bring the coils of the tensioning member into 125 closer relation when using fine count or small yarn, and similarly, when a yarn of coarser count or larger thread is employed, the ad- 130

justing member 15 may be moved in the opposite direction, whereupon the expansive coil action of the tensioning member will automatically separate the convolutions to accommodate the size of the thread in use.

From the construction described as one good form of the present invention, it will be noted, as shown in Fig. 2, that when the thread is under control of the guiding device or scroll, it will be drawn from the bobbin chamber into a plane sufficiently low to cause the thread to remain between the coils of the spring tensioning member, and should an overthrow occur as the shuttle is brought to rest in the replenishing box, the thread *a* may pass upwardly from the spring tensioning member and be cast upwardly out of the thread passage by the thread casting and guiding scroll.

It is believed this is the first instance in the art where a thread tensioning member constituted as a spring coil has been associated with an automatically threading shuttle for looms and positioned at the entrance to the longitudinally extending thread passage adjacent the bobbin chamber, so that the swirling action of the thread as it is withdrawn from the bobbin will cause the thread to automatically be engaged between the coils of the spring tensioning member, and yet permit such thread on the occurrence of an overthrow to pass upwardly from the thread passage. It will also be apparent that the thread guiding device for directing the thread to the side delivery eye during weaving is mounted in the longitudinally extending thread passage between the coiled spring tensioning member and the side delivery eye, so that when once the shuttle is threaded, the thread guiding device will maintain the thread in its tensioning position between the coils of the spring tensioning member.

What is claimed is:

1. In an automatically threading shuttle for looms, the combination of the shuttle having a longitudinally extending thread passage provided with a bridge at its forward end and side delivery eye, a resilient tensioning member at the entrance of the thread passage adjacent the bobbin chamber, and a thread guiding device in the thread passage between the tensioning member and the bridge at the forward end of the longitudinal thread passage to depress the thread into the tensioning member, as the thread is withdrawn from the shuttle on the first pick of the shuttle following replenishment.

2. In an automatically threading loom shuttle, the combination of the shuttle having a longitudinally extending thread passage, a resilient tensioning member at the entrance of the longitudinally extending thread passage adjacent the bobbin chamber,

and a thread casting and guiding device in the thread passage between the resilient tensioning member and the side delivery eye.

3. In an automatically threading loom shuttle, the combination of the shuttle having a longitudinally extending thread passage, a resilient tensioning member at the entrance of the longitudinally extending thread passage adjacent the bobbin chamber, and a scroll device in the longitudinally extending thread passage between the resilient tensioning member and side delivery eye.

4. In an automatically threading loom shuttle, the combination of the shuttle having a longitudinally extending thread passage, a resilient tensioning member at the entrance of the longitudinally extending thread passage adjacent the bobbin chamber, and a thread guiding scroll in the thread passage having a part thereof below the top of the tensioning device to cause the thread to pass into control of the tensioning device as the shuttle is threaded.

5. In an automatically threading shuttle for looms, the combination of the shuttle having a longitudinally extending thread passage and side delivery eye, a coiled spring tensioning device at the entrance to the thread passage adjacent the bobbin chamber, and a scroll in the thread passage between the coiled spring tensioning device and side delivery eye.

6. In an automatically threading shuttle for looms, the combination of the shuttle having a longitudinally extending thread passage and side delivery eye, a coiled spring tensioning device at the entrance to the thread passage adjacent the bobbin chamber, and a thread casting and guiding scroll in the thread passage between the coiled spring tensioning device and side delivery eye.

7. In an automatically threading shuttle for looms, the combination of the shuttle having a longitudinally extending thread passage and side delivery eye, a coiled spring tensioning device at the entrance to the thread passage adjacent the bobbin chamber, a thread casting and guiding scroll in the thread passage between the coiled spring tensioning device and side delivery eye, and means for adjusting the tensioning effect of the coiled spring.

8. In an automatically threading shuttle for looms, the combination of the shuttle having a longitudinally extending thread passage, a coiled spring thread tensioning member at the entrance to the thread passage adjacent the bobbin chamber, and a support for the coiled spring tensioning member secured to the shuttle body to position the coiled spring for engagement by the thread as it is withdrawn from the bobbin chamber.

9. A thread tensioning device for automatically threading shuttles for looms, com-

- 30
1. Comprising a coiled spring between the convolutions of which the thread is drawn; a supporting saddle for the coiled spring secured to the shuttle adjacent the bobbin chamber.
- 35
2. A thread tensioning device for automatically threading shuttles for looms, comprising a coiled spring between the convolutions of which the thread is drawn, a supporting saddle for the coiled spring secured to the shuttle adjacent the bobbin chamber.
- 30
3. to position the coiled spring to cause the unwinding thread as it is withdrawn from the bobbin to enter between the coils of the spring, and thread guiding means for directing the unwinding thread at the entrance to the thread passage into engagement with the coiled spring.
- 40
4. 10. A thread tensioning device for automatically threading shuttles for looms, comprising a coiled spring between the convolutions of which the thread is drawn, a supporting saddle for the coiled spring secured to the shuttle adjacent the bobbin chamber.
- 45
5. to position the coiled spring to cause the unwinding thread as it is withdrawn from the bobbin to enter between the coils of the spring, and thread guiding means for directing the unwinding thread at the entrance to the thread passage into engagement with the coiled spring.
- 50
6. 15. A thread tensioning device for automatically threading shuttles for looms, comprising a coiled spring between the convolutions of which the thread is drawn, a supporting saddle for the coiled spring secured to the shuttle adjacent the bobbin chamber.
- 55
7. to position the coiled spring to cause the unwinding thread as it is withdrawn from the bobbin to enter between the coils of the spring, and thread guiding means for directing the unwinding thread at the entrance to the thread passage into engagement with the coiled spring.

8. Comprising a coiled spring between the convolutions of which the thread is drawn; a supporting saddle for the coiled spring secured to the shuttle adjacent the bobbin chamber.

35

9. to position the coiled spring to cause the unwinding thread as it is withdrawn from the bobbin to enter between the coils of the spring, and means for supporting the coiled spring relative to the saddle in position to intersect the path of the thread in the thread passage.

40

10. 12. An automatically threading shuttle for looms having a side delivery eye and a threading block provided with a longitudinally extending thread passage, a thread tensioning member at the entrance of the thread passage adjacent the bobbin chamber, and a thread guide secured in the longitudinally extending thread passage between the tensioning member and the front end of the passage and below the top of the threading block to act upon the thread as it is delivered from the shuttle and cause it to be drawn through the thread tensioning member on the first pick following replenishment.

11. In testimony whereof, I have signed my name to this specification.

JOHN W. GILES.
